UNITED STATES PATENT OFFICE.

LOUIS N. D. WILLIAMS, OF OGONTZ, PENNSYLVANIA.

TAKE-UP DEVICE FOR KNITTING-MACHINES.

1,129,935.

Specification of Letters Patent.

Patented Mar. 2, 1915.

Application filed June 19, 1913. Serial No. 774,593.

To all whom it may concern:

Be it known that I, LOUIS N. D. WILLIAMS, a citizen of the United States, residing in Ogontz, Pennsylvania, have invented certain Improvements in Take-Up Devices for Knitting-Machines, of which the following is a specification.

The object of my invention is to produce a ribbed knitted fabric of different texture in different courses, an object which I attain in the manner hereinafter set forth, reference being had to the accompanying drawing, in which—

Figure 1 illustrates, partly in side elevation and partly in vertical section, a knitting machine constructed for carrying out my invention; Fig. 2 a side view illustrating a modification of my invention, and Fig. 3 a vertical sectional view illustrating another modification of the same.

In producing a ribbed knitted web for certain articles of apparel, such as ladies' undershirts or vests, it is advisable to make some portions of the web, such, for instance, as those intended to produce the bust and skirt portions of the shirt, wider than the other portions, such, for instance, as those intended to produce the waist portion of the shirt. This has been heretofore accomplished by knitting the bust and skirt portions with tuck stitches and the waist portion with plain stitches which has the effect of contracting the fabric in said waist portion. An objection to this fabric, however, is that the bust and skirt portions are relatively coarse and heavy as compared with the waist portion. In order to overcome this objection a fabric having plain stitches throughout has been devised, such fabric having a relatively heavy yarn in the bust and skirt portions and a finer yarn in the waist portion.

In carrying out my invention I produce or aid in the production of the change in texture by changing the distance between the knitting edge of the needle cylinder and the tensioning take-up device with which the knitting machine is usually provided. I may knit the fabric with yarn of the same character throughout relying wholly upon the change in the duration of the tension period for modifying the texture of the web in one portion as compared with that in another portion, but I prefer to knit the web in accordance with the second method above referred to, that is to say by using a rela-

tively heavy yarn in those portions of the web which are to be of the greater diameter and a finer yarn in those portions of the web which are to be of the lesser diameter.

The preferable method of effecting change in the relation of the tensioning take-up to the knitting edge of the needle cylinder is to employ two of such take-up devices, one above the other, and to use the one which is nearest the knitting edge of the cylinder when knitting the web of greater diameter and the one which is farthest from the knitting edge of the cylinder when knitting the web of lesser diameter. The same object can, however, be attained by the use of a single take-up device which is so mounted upon the frame of the machine as to be adjustable toward or from the knitting edge of the cylinder, or a single take-up device may be used in combination with a reducing ring on the inside of the needle cylinder, this ring being adjustable so that when it is in its contracted condition it will deflect the web in its passage from the upper edge of the cylinder to the take-up rolls and when in its expanded condition will permit the web to pass in a direct course from the upper edge of the needle cylinder to said take-up rolls.

In Fig. 1 of the drawing I have illustrated the machine as equipped with two take-up devices one above the other. These take-up devices may be similar to those heretofore employed which, in addition to taking up the web as produced also serve to impart tension thereto. Each take-up consists of a pair of rolls 1—1 carried by shafts 2—2 mounted in bearings in a vertically swinging frame 3 which is pivoted at 4 on some member of the fixed frame of the machine, the bearings for one of the shafts 2 being fixed and those for the other shaft 2 being acted upon by springs 5 so as to normally maintain the rolls 1 in driving contact with the knitted web which passes down between them. That one of the shafts 2 which is adapted to stationary bearings is provided with a worm wheel 6 driven by a worm 7 on a shaft which is also provided with a bevel wheel 8, the latter meshing with a bevel wheel 9 on a shaft 10 provided with a pulley 11. In the case of the upper take-up mechanism this pulley is driven by a belt 12 from a pulley on the main driving shaft 13 of the machine but in the case of the lower take-up mechanism said pulley 11 is driven

by a belt 14 from a pulley 15 on the shaft 10 of the upper take-up device. The weight of the take-up rolls, and their hanger 3 and the driving mechanism for the rolls, is borne by the knitted web which is therefore subjected to tension dependent upon the weight of the take-up mechanism. If, therefore, the upper set of take-up mechanism is in action such tension will be exerted throughout a shorter length of web and time than if the lower set of take-up mechanism is operative and the upper set is released from the web. I have found that this change has a material effect in varying the texture of the knitted web, the rule being that the longer tension period best agrees with the production of web of fine texture and the lesser period with the production of web of fuller or coarser texture. In connection with the two sets of take-up mechanism, therefore, I employ means for rendering at will either set of take-up mechanism operative upon the knitted web and the other set inoperative. The means shown in the drawing for accomplishing this result are a bell crank lever 16 mounted upon the shaft of the movable take-up roll 1, the short arm of this lever bearing against a shoulder 17 on the roll carrying frame and the long arm of the lever being connected by a link 18 to an arm 19 on a hub 20, the latter being mounted so as to be free to turn on the pivot pin 4 of the take-up roll carrying frame and having another arm 21 which is connected by a link 22 to an arm 23 pivoted upon a stud 24 on the upper portion of the supporting frame work of the machine, this arm being under control of a pattern chain 25 carried by a drum 26 to which intermittent movements of partial rotation are imparted by mechanism which may be similar to that ordinarily employed in knitting machines for operating the pattern chain drums thereof.

The pattern chain carries lugs 27 which are in different planes, one coinciding with that of one of the arms 23 and the other with that of the other arm. When either arm 23 is lifted it will, through the medium of the connecting devices described, swing outward, in the direction of the arrow x , the bell crank lever 16 coöperating therewith, thereby separating the corresponding take-up roll 1 from the opposite roll and rendering the take-up mechanism for the time being inoperative, as shown in the lower set of take-up mechanism in Fig. 1 of the drawing. When, however, the arm 23 rests upon the surface of the pattern chain 25 the bell crank lever 16 is free to move in the direction of the arrow y and the spring 5 therefore presses the movable take-up roll 1 toward the opposite roll and thereby renders the take-up mechanism active, as shown in the upper set. By a proper disposition of the lugs 27 upon the

pattern chain 25, therefore, either of the take-up devices can be put into action simultaneously with the putting out of action of the other. Each of the links 18 is slotted for the reception of the pin on the coöperating arm 19 so that the rising and falling movements of the take-up roll carrier will not, when the rolls are in operative relation, cause separation of said rolls.

In Fig. 2 I have illustrated a single take-up mechanism vertically adjustable on the fixed frame of the machine so as to vary its relation to the edge of the knitting cylinder, the take-up carrying frame 3 in this case being pivoted to a shaft 4 which is mounted upon a slide 30 adjustable vertically on a vertical web 31 which constitutes part of the fixed frame of the machine. When a vertically adjustable take-up device of this character is used the belt 12 which drives the pulley 11 will have to be changed when the change in the vertical adjustment of the take-up mechanism is effected or a belt tightener will have to be employed to automatically take up or let out the belt 12, as required.

In Fig. 3 I have shown the machine as provided with a ring 32 inside of the knitting cylinder, this ring being so constructed that it can be expanded as shown by full lines in order to permit the web to pass directly from the edge of the knitting cylinder to a take-up device or so as to be contracted in order to deflect the web as shown by dotted lines and thus increase the distance between the edge of the knitting cylinder and the take-up rolls.

I claim:

1. As a means for varying the texture of a knitted web, the combination of the knitting machine with means for applying tension to the web at one or the other of two relatively fixed points at different distances from the knitting point, and means for changing the point of application of tension when it is desired to change the texture of the web.

2. As a means for varying the texture of a knitted web, the combination of the knitting machine with two tensioning take-up devices, each permanently located at a definite distance from the knitting edge of the needle carrier and one being farther removed from said edge than the other, and means for causing these devices to engage alternately with the knitted web.

3. As a means of varying the texture of a knitted web, the combination of two tensioning take-up devices located at different distances from the knitting edge of the needle cylinder and each having web engaging rolls, one of which is movable from and toward the other, a pattern chain, a pair of arms acted upon thereby, and means where by one of said arms is caused to act upon

the movable roll of one take-up device and the other is caused to act upon the movable roll of the other take-up device to move the same from and toward the roll which co-
5 operates therewith.

4. The combination, in a take-up device, of web engaging rolls one of which is movable from and toward the other, a pattern chain, an arm acted on thereby, a lever acting upon the shaft of the movable take-up roll, and connections between said arm and lever whereby movement of the arm is
10

caused to effect movement of the take-up roll into or out of operative relation with its coöperating roll, said connections being slotted to compensate for movement of the take-up roll carrier. 15

In testimony whereof, I have signed my name to this specification, in the presence of two subscribing witnesses.
